WREATH-FORM AND THE PROCESS OF MANUFACTURING THE SAME.

1,194,462.

Specification of Letters Patent. Patented Aug. 15, 1916.

To all whom it may concern:

Be it known that I, HYMAN B. ABRAMS, a citizen of the United States, residing at Chicago, in the county of Cook and State of Illinois, have invented certain new and useful Improvements in Wreath-Forms and the Process of Manufacturing the Same, of which the following is a full, clear, concise, and exact description, reference being had to the accompanying drawings, forming a part of this specification.

My invention relates to improvements in wreath forms, hollow articles of paper, and the process of manufacturing the forms or articles.

One of the objects of my invention is the provision of a wreath form of paper which can be cheaply manufactured, which is light in weight, rigid in construction and impervious to moisture.

In the manufacture of the forms or articles I provide a heated form or a pair of dies adapted to press a sheet of paper or materials into the required shape, and an important feature of the invention resides in treating the paper before being acted upon by the dies with a coating of glue, so that it becomes moist and pliable, permitting forming of the sheet of paper, and so that the sheet after being formed becomes stiff and rigid, the glue hardening, due to the effect of the heat transmitted to it from the dies.

In carrying out the objects of the invention I provide coöperating male and female dies, one being heated by gas, steam or any other suitable means. The sheet of paper of which the articles are made is formed of a layer of card board like material such as pulp board, chip board or straw board, a coating of glue on one or both sides thereof, and a layer of flexible material which is preferably impervious to moisture over the glued surface of the straw board. The layer of impervious material performs several functions in that it prevents the sheet from adhering to the dies, assists in securing a rigid finished article and prevents the admittance of moisture into the card board after the sheet is formed into the shape of the article. To insure rigidity and to prevent the card board from tearing I provide an additional layer of reinforcing material such as buckram or rice net to the sheet and a wire binding around either one or both edges of the wreath form. This buckram

and wire binding not only make the form generally stronger, but positively prevent cutting into the card board when ornamental thread or wire roping is wound around the form.

In the accompanying drawings I have illustrated my improved wreath form and the process of manufacture thereof, but I wish it to be understood that the process may be employed with equal facility in the manufacture of other hollow articles, such, for example, as lamp shades, boxes, etc.

In the drawings Figure 1 illustrates a vertical cross sectional view of a sheet consisting of several layers which is acted upon by the dies and formed into the shape of a wreath form or any other article desired. Fig. 2 is an enlarged cross sectional view of a portion of the sheet shown in Fig. 1. Fig. 3 is a cross sectional view of the die members showing a paper form between the members. Fig. 3^a is a perspective view of the wooden block employed for pressing the sheet of materials into the general shape of the wreath form before the sheet is given the final form. Fig. 4 is a plan view of the finished wreath form as it is taken from the dies. Fig. 5 is a view similar to Fig. 4 showing the wreath form covered with ornamental roping. Fig. 6 is a cross sectional view taken along the lines 6—6 of Fig. 5, and Figs. 7 to 11 inclusive illustrate modifications of the wreath form.

The sheet of materials from which the preferred form of wreath form is produced is illustrated in Fig. 1, and consists of a layer of card board like material 12 provided with a coating of glue 13 on its upper surface and a similar coating of glue 14 on its lower surface. In order to make the card board more flexible and pliable it may be moistened with water before the coatings of glue are applied. A sheet of impervious paper 15 is then placed over the coating of glue 13, and a circular buckram or rice net piece 16 placed over the coating of glue 14. This buckram or rice net is circular in shape and has a diameter which is slightly greater than the inside diameter of the completed wreath form. A coating of glue 17 is then applied to the exposed surface of the buckram and the layer of impervious paper 18 placed over the last mentioned glued surface and the glued surface of the card board 12 left uncovered by the buckram. On account of the

moisture contained in the glue the card board is rendered flexible and pliable, and while it is still moist it is placed upon the male die 19 and formed by hand around the 5 annular portion 20 of the die. This manual forming of the sheet of materials is desirable in order to first form the sheet into approximately the shape desired and to fold over the excess material as indicated at 10 21-21 in Fig. 4. The male die 19 contains a chamber 22 which is heated by gas, steam or any other suitable means. After the sheet of materials has been pressed around the male die 19 by hand, the wooden block 15 23^a is inserted on the inner side of the ridge 20, as illustrated in Fig. 3, and the female die 23 caused to move downwardly. This step of the process forces only the inner portion of the sheet of materials tightly around 20 the ridge 20 and thus prevents tearing, which would occur if the sheet were held on the outside of the ridge. After the inside of the form is thus pressed, the female die 23 is raised and the block 24 removed. The fe- 25 male die 23 is then lowered to the position illustrated in Fig. 3 to tightly press the sheet into the shape of the annular ridge 20 of the male die. The die members are held in closed position until the heat of the die 19 30 hardens the several coatings of glue on the sheet and makes the glue stiff and rigid. The dies are then separated and the partly completed wreath form removed.

Attention is called to the fact that on account 35 of the impervious layers of paper 15 and 18 the glue is prevented from adhering to the die members when the dies are separated. When the form is removed from the dies the inner flat portion 24 and the flange 40 25 are cut out by means of a knife or a pair of scissors. The buckram layer prevents tearing of the card board when the sheet is placed between the dies and in the preferred construction lies only on the inside of the 45 completed form, as illustrated in Fig. 10, and serves to reinforce this portion of the form. To reinforce the outer edge of the form a wire 25' may be sewed around the outer periphery of the form (Fig. 10).

50 Figs. 5 and 6 illustrate one form of ornamentation which may be placed upon the completed wreath form. The ornamentation illustrated in the drawing consists of colored roping 26 wound around the form 55 and fixed thereto in any suitable manner to prevent removal thereof. The wreath form may, of course, be used for flowers, etc., in that the card board like material is protected from the moisture of the flowers by means 60 of the layers of impervious paper glued around the outside of the form.

Fig. 7 illustrates a modification wherein the buckram or rice net 16 extends entirely across the form and reinforces the entire 65 semi-circular cross section thereof. The

buckram or rice net also prevents the ornamental roping from cutting into or tearing the card board when it is wound around the form.

In Fig. 8 buckram or rice net is eliminated 70 and only the card board, coats of glue and layers of impervious material employed.

Fig. 9 illustrates a modification wherein a wire binding is employed at 26' around the outer edge of the form and a reinforcing 75 piece of card board 30, and a layer of paper 31 over the card board sewed to and around the inner edge of the form.

Fig. 10 illustrates in detail the construction 80 of the form shown in Fig. 4, and in addition thereto a wire binding 25' around the outer edge of the form.

In Fig. 11 the inner edge is reinforced by a rice net collar 27 carrying the wire binding 28. This collar 27 is sewed to the layers of 85 card board and paper and serves to reinforce the inner edge of the form.

Attention is called to the fact that if the card board 12 were used alone, that is, without the other layers of paper, it would not 90 form a rigid article but could be easily bent, torn or broken, or it would become flat or pliable if it were subjected to moisture. Since, however, the layers 15 and 18 are employed outside of the coatings of glue a very 95 stiff and rigid structure is obtained, the layers 15 and 18 combining with the glue to keep the card board in the shape of the article.

Although I have described the layers 15 100 and 18 as being preferably made of impervious paper, I wish it to be understood that cloth or any other reinforcing material may be employed, although impervious paper has its advantages in that moisture is positively 105 prevented from entering the card board.

Having thus described my invention, what I claim as new and desire to secure by Letters Patent of the United States, is:

1. The manufacture of hollow articles 110 which consists in applying a coating of glue to one side of a sheet of card board like material, laying a sheet of paper over the glued side of the material, and pressing the sheet of materials while still moist around a heated form, whereby the glue is dried while the sheet is around the form and after the sheet is formed into the shape of the hollow article. 115

2. The manufacture of hollow articles 120 which consists in applying a coating of glue to both sides of a sheet of card board like material, laying a sheet of paper over the glue on both sides of the card board and pressing the sheet of materials while still 125 moist around a heated form, whereby the glue is dried while the sheet is on the form and after the sheet is formed into the shape of the hollow article.

3. A wreath form of substantially semi- 130

- circular cross section comprising super-imposed layers of paper, card board, buckram and paper, in the order given, glued together to form a rigid structure.
- 5 4. A wreath form of substantially semi-circular cross section comprising super-imposed layers of paper, card board, rice net and paper, in the order given, glued together to form a rigid structure.
- 10 5. A wreath form of substantially semi-circular cross section comprising super-imposed layers of paper, card board, buckram and paper, in the order given, glued together to form a rigid structure, and wire 15 binding around the outer edge of the form.
6. A wreath form of substantially semi-circular cross section comprising super-imposed layers of paper, card board, rice net and paper, in the order given, glued together 20 to form a rigid structure, and wire binding around the outer edge of the form.
7. A wreath form of substantially semi-circular cross section comprising super-imposed layers of paper, card board like material and paper, in the order given, glued together to form a rigid structure, and wire 25 binding around the outer edge of the form.
8. The manufacture of wreath forms which consists in applying a coating of glue 30 to both sides of a sheet of card board, placing a sheet of paper over one of the glued sides, placing a layer of buckram on the other glued side, coating the upper surface of the buckram with glue, placing a layer of paper over the glued surface of the buckram and pressing the sheet of materials while still moist between two heated dies, whereby the glue is dried while the sheet is between the dies and after the sheet is formed into the shape of the wreath form. 35
9. The manufacture of wreath forms of substantially semi-circular cross section, which consists in applying a coating of glue to both sides of a sheet of card board, placing the sheet of paper on one of the glued 40 sides, laying a circular piece of buckram over the other glued side, the diameter of the buckram piece being slightly greater than the inside diameter of the completed wreath form, so as to reinforce only the inner side of the form, coating the upper surface of the buckram, placing a layer of paper over the buckram and the straw board uncovered by the buckram, and pressing the sheet of materials while still moist between 45 two heated dies, whereby the glue is dried while the sheet is between the dies and after the sheet is formed into the shape of the wreath form. 50
- 55 In witness whereof, I hereunto subscribe my name this 29th day of March, A. D. 1916.
